UNITED STATES PATENT OFFICE.

JAMES HENRY GREGORY AND FOREST MARSH SHUMWAY, OF FARWELL, MICHIGAN.

CUSPIDOR.

936,774.

Specification of Letters Patent.

Patented Oct. 12, 1909.

Application filed April 30, 1909. Serial No. 493,182.

To all whom it may concern:

Be it known that we, JAMES HENRY GREGORY and FOREST MARSH SHUMWAY, citizens of the United States, and residents of Farwell, in the county of Clare and State of Michigan, have invented a new and Improve Cuspidor, of which the following is a full, clear, and exact description.

The invention is an improvement in cuspidors, and belongs to that class of such devices in which provision is made for discharging the contents of the bowl at the bottom when the cuspidor is washed out.

The invention has in view a cuspidor of this character having side portions hinged at the top to swing outwardly from the base, and provided with a hopper bottom inclining from the center toward each hinged side portion, to insure ready discharge and easy

20 cleansing.

The invention further contemplates means normally tending to force the hinged side portions closed, and a ring, slideable around the neck of the cuspidor to spread the sides 25 apart and hold them open against the tension of the said means.

Reference is to be had to the accompanying drawings forming a part of this specification, in which similar characters of reference indicate corresponding parts in all the 30 views.

Figure 1 is a central vertical section of a cuspidor constructed in accordance with our invention; Fig. 2 is a cross-section through the body of the cuspidor substantially on the line 2—2 of Fig. 1; Fig. 3 is a similar section of the cuspidor on the line 3—3 of Fig. 1; Fig. 4 is a section of the cuspidor on the line 4—4 of Fig. 2; Fig. 5 is a section of the 40 cuspidor on the line 5—5 of Fig. 6; and Fig. 6 is a view similar to Fig. 1, with the hinged side portions of the cuspidor swung open.

The cuspidor is made up of the customary principal portions, such as the funnel 10, neck 11 and bowl 12, the latter having a flattened base of sufficient extent to insure stability and provided with oppositely-arranged side portions 13 hinged at the top, as indicated at 14, to swing outwardly from the bottom, as shown in Fig. 6. The bowl is constructed with a hopper bottom 15 which inclines from the center downwardly to each of the hinged side portions 13. The hinged side portions 13 are extended a short 55 distance above the hinges, as indicated at 13^a,

where they incline upwardly and outwardly from the neck, as shown in Fig. 6, and incline inwardly toward the neck at each end, as shown in Fig. 3. Between the extended portions 13^a and the neck of the cuspidor are 60 fixed V-shaped springs 16, tending to force the side portions 13 closed. The springs 16, however, are not solely depended upon to perform this function, but springs 17 attached to the hopper bottom and to the 65 lower portions of the hinged sides forcibly pull the hinged side portions to the bowl. Leak-proof joints between the hinged side portions and the bowl are insured by providing the contacting edges with tongues 70 and grooves, as shown in Fig. 1, and lining the groove with a rubber or other gasket 18.

Around the neck of the cuspidor is a rotatable ring 19 of sufficient diameter to close and freely move over the extensions 75 13^a. This ring is shown to be longitudinally curved, with the convex face arranged outwardly to bear at the top and bottom edges of the funnel and bowl respectively. The ring 19 is provided with handles 20 by which 80 it is rotated, and also with cams 21 on its inner face at diametrically opposite points, each cam having a central notch and designed to pass to the outside of the extensions 13^a and thereby spread the hinged side 85 portions 13 apart and hold them open against the tension of the springs 16 and 17, as when the cuspidor is being washed out. The free passage of the cams to the outside of the extensions 13^a is insured on revolving 90 the ring, by reason of the inwardly-inclined end portions of the extensions above referred to. The notches in the center of the cams are engaged by the central portions of the extensions 13^a, as shown in Fig. 6, thus freely 95 retaining the ring in place when the hinged side portions are fully opened. When the hinged side portions of the cuspidor are opened, the rapid discharge of the contents and thorough cleansing of the cuspidor is 100 insured by the hopper bottom 15.

Having thus described our invention, we claim as new and desire to secure by Letters Patent:

1. A cuspidor having side portions hinged 105 at the top to swing outwardly at the bottom, and provided with a hopper bottom inclining from the center of the cuspidor toward the hinged side portions.

2. A cuspidor having movable side por- 110

tions, and a revolute member encircling the cuspidor having means to move the side portions to an open position.

3. A cuspidor having a side portion hinged to swing outwardly at the bottom, means tending to force the hinged side portion closed, and a rotatable ring arranged around the neck of the cuspidor, having means to force the hinged side portion open against the tension of said means.

4. A cuspidor having a side portion hinged at the top to swing outwardly at the bottom, and provided with an extended portion above the hinge, and a rotatable ring surrounding the neck of the cuspidor, having a cam to engage the extension of the hinged side portion and force the side portion open.

5. A cuspidor having side portions hinged

at the top, each side portion having an extension above its hinge, a hopper bottom 29 inclining downwardly from the center toward each hinged side portion, springs tending to force the hinged side portions closed, and a rotatable ring encircling the neck of the cuspidor, having cams to engage with 25 the extensions of the hinged side portions and force the said portions open against the tension of the springs.

In testimony whereof we have signed our names to this specification in the presence 30 of two subscribing witnesses.

JAMES HENRY GREGORY.
FOREST MARSH SHUMWAY.
